UNITED STATES PATENT OFFICE.

JOSEPH N. GRENIER, OF BOSTON, MASSACHUSETTS.

SKYLIGHT.

No. 880,654.

Specification of Letters Patent. Patented March 3, 1908.

Application filed May 27, 1907. Serial No. 375,973.

To all whom it may concern:

Be it known that I, JOSEPH N. GRENIER, a citizen of the United States, residing at Boston, in the county of Suffolk and State of Massachusetts, have invented certain new and useful Improvements in Skylights, of which the following is a specification.

My invention relates to skylights for buildings and has for one of its objects the improvement of the construction of the supporting bar which is of the inverted channel beam type by providing an integral drain or gutter at each side, a drain or gutter centrally of its top having converging sides, and a longitudinal groove at each side of the central gutter to receive a cushion for the glass plates, said cushion comprising a tube of soft metal such as lead. The bolts to fasten the cap in place are secured in holes 20 in the central drain and have nuts thereon with beveled sides to fit the converging sides of the drain so that the head of the bolt is drawn into the hole in the drain to make a water tight joint.

Another object of my invention is the improvement of the metal caps used for covering the longitudinal joints of the glass plates by forming them with a curved base portion to seat on the glass which before installing 30 in position is filled with putty or cement to make a substantially weather-proof connection between the glass plates and the cap.

The construction and advantages of my invention will be described in detail herein-after and illustrated in the accompanying drawings in which—

Figure 1 is a fragmental plan view of a skylight involving my invention, Fig. 2, a fragmental cross section through one of the 40 supporting beams, Fig. 3, a longitudinal sectional view on the line x—x of Fig. 2 looking in the direction of the arrow, and Fig. 4, a view showing a modification of the cushion.

In the drawings similar reference characters indicate corresponding parts throughout the several views.

The supporting beams or bars 1 of my improved skylight are, as shown, of the inverted channel beam type and are provided with a longitudinal gutter 2 at each side formed integral with the beam 1 and having slanting outer sides 3. The top of the beam has a drain or gutter 4 formed therein and running longitudinally of the center of the beam the

sides of said drain or gutter being slanting 55 or converging as shown at 5.

6 indicates a longitudinal groove or depression at each side of drain 4.

In practice the beam just described can be made the most economically by rolling but it can be made in any other manner desired.

The grooved portions 6 of the beam or bar 1 have the metal cut out on three sides and turned up at intervals as shown at 7 to form abutments against which rest the lower edges 65 of the plates of glass 8 which constitute the surface of the skylight.

9 indicates lengths of soft metal tubing resting on the grooved portions 6 between the abutments 7 on which the inner surfaces 70 of the glass plates 8 rest. The surfaces of the glass plates used in constructing skylights are uneven and by having the cushions made of tubes of soft metal, as stated, the unevennesses of the glass plates impress themselves 75 on the surfaces of the tubular cushions so as to make a water tight joint between the glass plate and cushion and prevent rain water, that may percolate through the joints, from following the inner surface of the glass, 80 but to follow the top of the beam or fall into the center gutter.

The caps 10 for covering the joints over the beams or bars 1 are formed with integral base portions 10^a curved slightly upwardly 85 from the glass plates and before being placed in position filled with putty, cement or other filling 11 to make a weather proof joint. The caps 10 are held in position by means of screw bolts 12 secured in holes in the bottom 90 of drain 4 which have beveled heads 13 to form a water tight joint with the holes, the bolts being held in position by means of nuts 14 having beveled sides 15 to fit the converging sides 5 of drain 4.

16 indicates a nut to secure the cap in position.

17 indicates the cross-bars or drains which are made of sheet metal having a flat portion 18 to seat on top of the upper surface of the 100 glass plate below the transverse joint then bent at right angles downwardly between the abutment 7 and the plate of glass as shown at 19, then at right angles upwardly under the lower surface of the upper plate as 105 shown at 20, then back on itself as shown at 21 beyond the joint between the plates. This portion of the transverse bar extends the full

width of the plates of glass and the parts 20 and 21 rest at each end on the tubular cushions 9 so as to support the transverse edges of the glass plates 8. The lower edge of the flat 5 portion 18 is bent downwardly as shown at 18^a to prevent the portion 16 from buckling.

The part 21 is cut out as shown at 21^a to avoid the abutment 7, and extended back thereof, then cut away as shown at 22 to 10 avoid the edge of the beam when bent downwardly as shown at 23 at right angles to part 21. The metal is then bent upwardly as shown at 24 on a plane substantially parallel to the portion 21 and then obliquely upwardly as shown at 25, the parts 23, 24 and 25 forming a drain or gutter to catch the water of condensation that forms on the inner surface of the glass plate 8. The ends of the portions 24 extend over the longitudinal 20 drains 2 of the beams or bars 1 and have downwardly bent lips 24^a formed integral with the part 24 to direct the water in the cross drain into drain 2.

The free ends of the parts 20 and 21 are cut 25 away from the part 19 and bent downwardly over the center drain 4 as shown at 21^a so as to direct any surface water that might get through a leak between the cap and glass plates, and follow down the inner surface of 30 the glass and the cushion 9, into the drain to be carried off.

The lowermost transverse drains are formed of continuous plates of sheet metal bent to form an upright portion 26, then bent at 35 right angles thereto as shown at 27, then bent downwardly between the lowermost abutment 7 and the lower edges of the lowermost glass plates, then upwardly at right angles as shown at 28 between the inner edges of the 40 plates of glass and the cushions 9, then back on itself as shown at 29, the parts 28 and 29 extending the full length of the plate of metal to form rigid cross bars to support the lower edges of the glass plates. The parts 45 between the beams 1 are cut away and bent downwardly as shown at 30 then upwardly as shown at 31 and finally obliquely upwardly as shown at 32 to form the drain. The edges of the parts 31 are bent downwardly as 50 shown at 33 to form integral lips to direct the water from the drains formed by the parts 30, 31 and 32 into the drains 2.

The upper edges of the uppermost plates of glass are held in position by means of a 55 clamping member made of sheet metal having a portion 34 to lie on top of the plate with its lower edge bent downwardly as shown at 35 to prevent buckling. The metal is bent downwardly at right angles to part 34 as 60 shown at 36 along the upper edge of the glass plate, then at a right angle as shown at 37 under the upper edge of the glass plate then back on itself as shown at 38 and finally downwardly as shown at 40. The parts 37

and 38 form a rigid cross-bar to support the 65 upper edges of the plates of glass 8.

From this description of my invention it will be apparent that all condensation of moisture that forms on the inner surface of the glass plates are taken care of by the cross 70 bars or drains 17 while rain water is kept out by means of the cement or putty 11 but should a leak occur between the caps 10 and the glass plates 8 the water will be caught by the drain 4 and carried off, the tubular 75 cushions 9 as stated above preventing the water from creeping along the inner surface of the plates. Also as each plate of glass is supported by means of the abutments 7 the weight of the skylight is evenly distributed 80 over the supporting beams 1 and the lower plates relieved of the crushing weight of the upper plates of glass.

I have shown and described the cushion 9 made of a tube of soft metal such as lead but 85 it will be understood that I can use a solid bar of any soft metal as lead or its like as shown at 9^a in Fig. 4 without altering the spirit of my invention.

Having thus described my invention what 90 I claim is—

1. In a skylight, the supporting beams formed with longitudinal grooves, cushions resting in said grooves formed of tubes of soft metal, and the glass plates resting on said 95 cushions, substantially as shown and described.

2. In a skylight, the supporting beams having portions cut out on three sides and turned up at intervals to form abutments, 100 and plates of glass resting on said beams and against said abutments, substantially as shown and described.

3. In a skylight, the supporting beams of the inverted channel beam type having the 105 upper surface cut out on three sides at intervals and turned up to form abutments, and plates of glass resting on said beams and against said abutments, substantially as shown and described.

4. In a skylight, the supporting beams formed of metal and having a central longitudinal drain, the parts of the beam at each side of said central drain cut out at intervals and turned up to form abutments, and plates 115 of glass resting on said beams and against said abutments, substantially as shown and described.

5. In a skylight, the supporting beams of the inverted channel beam type having a 120 central longitudinal drain in its upper surface the parts of the beam on each side of said central drain cut out at intervals and turned up to form abutments, and plates of glass resting on said beams and against said abutments, 125 substantially as shown and described.

6. In a skylight, the supporting beams made of inverted channel beams having lon-

itudinal drains at each side, a central longitudinal drain in the upper surface of the beam, a longitudinal groove on each side of the central drain, a cushion made of a tube of soft metal resting in each groove, and the glass plates resting on said tubes, substantially as shown and described.

7. A skylight comprising beams, tubular cushions of soft metal resting on said beams, the glass plates resting on said cushions, caps covering the joints over the beams having upwardly bent bases forming recesses between the caps and the plates of glass, and a weather proof filling contained in said recesses, substantially as shown and described.

8. A skylight comprising beams of the inverted channel beam type having their upper surfaces formed with central longitudinal gutters, the parts at each side of said central gutters cut out at intervals and turned up to form abutments, the intermediate portions between said abutments grooved, tubular cushions of soft metal resting in said grooves, and the glass plates resting on said cushions and against the abutments, substantially as shown and described.

9. A skylight comprising beams of the inverted channel beam type having their upper surfaces formed with central longitudinal gutters, the parts at each side of said central gutters cut out at intervals and turned up to form abutments, the intermediate portions between said abutments grooved, tubular cushions of soft metal resting in said grooves, the glass plates resting on said cushions and against the abutments, caps covering the joints over the beams having upwardly curved bases forming recesses between the bases and the glass plates, said caps being held in position by bolts secured through the bottoms of said gutters, and a weather proof filling contained in the recesses between the cap bases and the glass plates, substantially as shown and described.

45 10. A skylight comprising beams of the inverted channel beam type having side drains formed integral with the lower edges of the beams, central longitudinal drains having converging sides formed in the tops of the beams, the parts of the beams at each side of the central drain cut out at intervals and turned up to form abutments, the inter-

mediate portions between said abutments grooved, tubular cushions of soft metal resting in said grooves, the glass plates forming the surface of the skylight resting on said cushions and against said abutments, transverse drains supported between the abutments and the lower edges of the plates of glass having downwardly extending integral lips emptying into said side drains, caps covering the longitudinal joints of the glass plates over the beams having upwardly curved bases forming recesses between the bases and the glass plates, bolts secured through the bottoms of said central drains and having nuts thereon with beveled sides to engage the sides of said central drains, said bolts secured to said caps to hold them in position, and a weather proof filling contained in the recesses between the cap bases and the glass plates, substantially as shown and described.

11. In a skylight, beams, cushions resting on said beams formed of tubes of soft metal, and the glass plates resting on said cushions, substantially as shown and described.

12. In a skylight, beams, cushions resting on said beams formed of tubes of lead, and the glass plates resting on said cushions, substantially as shown and described.

13. In a skylight, beams, cushions resting on said beams formed of tubes of soft metal and glass plates having uneven under surfaces resting on said cushions, the cushions accommodating themselves to the unevenness in the glass and beam so as to form a watertight joint between the beam and glass, substantially as shown and described.

14. In a skylight, beams, cushions resting on said beams formed of tubes of lead, and glass plates having uneven under surfaces resting on said cushions, the cushions accommodating themselves to the unevennesses in the glass and beam so as to form a watertight joint between the beam and glass, substantially as shown and described.

In testimony whereof I hereto affix my signature in the presence of two witnesses.

JOSEPH N. GRENIER.
